UNITED STATES PATENT OFFICE.

ALONZO LINTON BAUSMAN, OF CHICOPEE, MASSACHUSETTS, ASSIGNOR TO NATIONAL EQUIPMENT COMPANY, OF SPRINGFIELD, MASSACHUSETTS, A CORPORATION OF MASSACHUSETTS.

REDUCING APPARATUS.

1,329,741.

Specification of Letters Patent.

Patented Feb. 3, 1920.

Application filed May 21, 1917. Serial No. 170,059.

To all whom it may concern:

Be it known that I, ALONZO LINTON BAUSMAN, a citizen of the United States of America, residing at Chicopee, in the county 5 of Hampden and State of Massachusetts, have invented certain new and useful Improvements in Reducing Apparatus, of which the following is a specification.

This invention relates to an improved 10 construction on the face or faces of co-operating reducing disks. Such disks as this invention is particularly concerned with are those which may be used to best advantage, for example, in the machine disclosed in my 15 United States Letters Patent No. 1,035,304, granted August 13, 1912. In refining the liquor obtained from the cocoa bean, for which said machine is designed, or in refining chocolate and the like, special problems 20 present themselves, and it has been found that ordinary grinding disks do not work properly. Much thought has been expended in designing the best form of reducing disk for the particular purpose of refining the 25 cocoa, chocolate, or the like to the best advantage. Successful disks have been produced, an example of which is found in my United States Patent No. 1,203,461, granted October 31, 1916.

30 Among the problems involved in producing successful refining disks for the stated purpose are in the order of their importance,—a disk face which will refine the liquor without burning, to avoid the caking 35 of the liquor on the disk and a resulting burning of the caked portions in spots, to provide a disk face which will refine the liquor fast enough to permit volume and certain production, and to provide a disk 40 face of relatively inexpensive construction.

According to one feature of the present invention, a novel form of disk face is provided consisting of several hundreds of pockets substantially covering the face of 45 the disk, each of which pockets is much greater in length than in width and which has a substantially vertical longitudinal face and another longitudinal face gradually sloping from the bottom of the pocket to the 50 outer face of the disk. These pockets are preferably arranged each at a small angle to any radius passing thereacross. This arrangement of pockets on the disk face is further characterized by the fact that the

pockets are arranged in substantially concentric series, the pockets of each series being generally separated from the pockets of adjacent series by dividing walls, the tops of which are in the same plane as the outer face of the disk. The end faces of the pockets preferably slope gradually to the tops of the dividing walls at about the same pitch as the longitudinal sloping walls. The disk face is further characterized by a series of spaced feeding grooves extending radially 55 and outwardly from the feed opening at the center of the disk to a point near the periphery of the disk where they slope gradually to the top of the dividing walls mentioned. These feeding grooves in effect constitute a 60 large pocket, like the series of more numerous pockets but they differ in this that they are deeper, open at their inner ends to the feed opening of the disk, and their perpendicular faces are substantially radial to the 65 disk, an arrangement which effects in the preferred embodiment a dipping into the feed grooves by the adjacent smaller pockets which are arranged at a slight angle to the radius. 70

According to another feature of the invention, the dividing walls between the ends of adjacent pockets in different series are arranged at an acute angle with respect to the feed grooves, whereby the ends of successive pockets in each series are located a slight distance nearer the periphery of the disk than the ends of succeeding pockets considered with respect to the direction of the disk's rotation past a fixed point. 75

According to another feature of the invention, certain pockets adjacent to the feed grooves open only at their inner ends into the feed grooves and pockets adjacent the periphery open at their outer ends to discharge their contents at the periphery. This arrangement is characterized by effective feeding and discharging means, whereby volume production is secured while at the same time the liquor traveling 100 from pocket to pocket as the disks rotate face to face is caused to pass over the longitudinal sloping faces of the pockets in a circular direction and generally up the end sloping faces over the dividing walls when 105 traveling outwardly from the pockets of one series to the pockets of the next outer series.

According to another important feature

of the invention, the form of disk face of the kind and for the purpose described may be effectively made by a casting operation for the form and arrangement of the reducing surfaces are in one aspect of the invention designed with particular reference to obtaining effective surfaces for the purpose by casting operations rather than by the more expensive and laborious process of cutting by milling machines. The advantage of casting over milling machine work is, of course, obvious, but the invention in this aspect resides in the structure of the disk for the really difficult operation of refining chocolate and which structure is effective for such operation and at the same time may be made by casting.

Other features of the invention will appear in the illustrative embodiment of it in the drawings.

Figure 1 is a sectional view of the arrangement of disk faces for operation in the machine of the patent above referred to;

Fig. 2 is a plan view of the novel disk face (in which only a portion of the disk is shown as finished to save needless labor in the drawing) as the same appears attached to a rotatable supporting plate keyed to a suitable shaft; a portion of the disk is cut away to show a view of the supporting plate;

Fig. 3 is a slide elevation of the rotatable plate showing its shaft and the disks as attached to the opposite faces of the plate;

Fig. 4 is a plan view of a separable segment of the disk showing on its face the preferred arrangement of pockets and feeding grooves;

Fig. 5 is a detail section on line 5—5 of Fig. 4;

Fig. 6 is a detail section on line 6—6 of Fig. 4;

Fig. 7 is a detail plan view similar to Fig. 4 but showing the reducing surfaces in the reverse order as would be necessary when right and left handed disks are used on the same rotatable plate in co-operation with adjacent face to face disks;

Fig. 8 is a cross section on line 8—8 of Fig. 7; and

Fig. 9 is a detail view of one way to arrange the disks for relative movement with respect to their reducing surfaces.

The form of the reducing surfaces on each disk make the latter susceptible to successful casting operations in the manufacture. This is important and new for a disk of the kind desired for it saves milling machine operations. A preferred way to make the disk of this invention is to first cut a master piece for use as a pattern. From this pattern by usual methods, eight pieces or 45° segments like that shown in Fig. 4 may be cast. These eight pieces may

be conveniently assembled and fastened to a supporting piece or disk 1, as indicated in Figs. 2 and 3, by headed screws 2. The heads of the latter are received by suitable recesses 3 and engage threads in tapped holes 4, all to the end that the segments are held to form a complete disk on each face of the supporting plate 1. The recesses 3 for the heads of the screws 2, it will be noted, are formed to prevent marring the reducing face of the disk and so that the purpose of the reducing surfaces of the latter will not be defeated even in spots.

As shown, feeding grooves 5 extend substantially radially from the center of the disk to a point close to but spaced from its periphery and are angularly spaced fifteen degrees apart. Each groove is preferably of the cross section shown in Fig. 8, and the bottom of the groove slopes gradually and radially from its deepest point at the center to the outside face of the disk at its outer end. Of course, these grooves could be formed in other ways and spaced different distances apart. For example, they might be V-shaped in cross section without defeating the purpose of feeding, but the preferred form is shown.

The pockets 6 are shown arranged in separate series of sets of pockets A, B, C, D, and E for the disk surface between successive feed grooves 5. It will be understood for purposes of convenience that a like series of sets of pockets A, B, C, D, and E are arranged for the surface over each segment between adjacent feed grooves 5 in the form of the invention shown as the preferred embodiment. Thus, an explanation of one such segment surface will apply logically to all. This series may be termed the radial series, characterized in order by the location of the inner end of the pocket of each set nearest the center of the disk around which the feeding space is located.

The preferable arrangement of the pockets which is considered new as well as other features of the invention can best be understood by the conception of the two series of sets, one radial and the other circular. The circular series are thought of as the corresponding sets in successive segments between feed grooves and may be indicated by the series designation, A—A³ etc., B—B³ etc., C—C³ etc., D—D³ etc., and E—E³ etc. Each set of pockets might be considered as a series, but it is preferred to designate all the pockets of one set as A, B, and the like. For example, counting from the lower lead lines in Fig. 4, toward the feed groove 5 and outwardly, the set A consists of six pockets, set B of six, set C of seven, set D of nine, and set E of six. This numerical arrangement can, of course, be changed to make a large

variety of arrangements with the use of the invention as an object. The purpose of specifying rather exactly the sets, the series, and the arrangement and boundary of the 5 pockets is to bring the scheme of the invention into clear relief and not to suggest that the invention resides in the exact arrangement of the form described.

Each pocket is preferably longer than it 10 is wide and is made with one surface substantially vertical and the other end surfaces gradually sloping to the outer face of the disk. This arrangement will lend itself to manufacture by casting, as such 15 pockets as well as the described feed grooves may readily be formed by such manufacture. The disk may be finished by grinding its plane face without spoiling the reducing surfaces. At the same time, the pockets and 20 the arrangement thereof are particularly adapted for their difficult purpose, as will appear.

The pockets of each set are arranged at a small angle to the radius passing through 25 each, and that pocket of the set nearest the center is made longest. The successive pockets of a set counting outwardly are generally shorter than the preceding pockets, and each is generally located nearer the periphery of 30 the disk or farther away from the central feeding point than the preceding pocket. This arrangement may be departed from to a limited extent, as a close examination of Fig. 4 will indicate. The general arrangement of pockets in this respect is desirable, but such arrangement is flexible in the broad aspect of the invention.

The narrow dividing walls 9, 10, and 11, 40 of small area on the outer face of the disk, form boundaries for the sets of pockets A—B, B—E, and C—D, respectively. The pockets 6 and feed grooves 5 are formed so that they merge, some into the other, as if each were separately cut without regard 45 to the other but with a purpose of having them functionally coöperate, as will appear.

The arrangement of reducing faces on 50 the disk has been described with particular reference to the segment below feed groove 5 in Fig. 4. All three segments shown in Fig. 4 correspond. The complete segment shown in Fig. 4 indicates one cast piece of the disk, such a piece as can be efficiently cast for convenience.

Enough of my prior patented machine 55 is indicated in Fig. 1 to show the most desirable assembly and use of the disks described which is known to me at this time. A rotatable shaft 12 has keyed thereto a 60 circular supporting plate 1. A complete 360 degree assembly of segments, as shown in Fig. 4, is fastened in the described manner to the right face of plate 1, and a like assembly of segments, but formed in reverse 65 fashion as indicated in Fig. 7, is fastened

to the left face of the plate. Corresponding assembled disks are likewise fastened to the inner faces of stationary jacketed castings J held in proper respective positions by bolts and springs b, as indicated. 70

This assembly with respect to coöperable disk faces and direction of rotation is best shown in Fig. 9. The right hand disks are R—R' and the left hand ones L—L', corresponding in surfaces to those shown in 75 Figs. 4 and 7, respectively.

The cocoa, chocolate, or other substance of like difficult refining qualities is fed to center space s by feed pipes F and outwardly in feed grooves 5 and pockets contiguous 80 thereto. The spaces between face to face disks are thus loaded with a material amount of the liquor. The plate 1 is rotated and the continued feeding of liquor (preferably under positive and measured constant pressure) takes place. The liquor tends to flow directly to the peripheral outlets O between the disks and to the discharge pan P. This direct flow is effectively prevented by the arrangement of pockets according to this 90 invention.

The filled pockets A and C of one disk with like filled pockets A and C of the adjacent face to face disk cannot readily discharge their contents on account of dividing 95 walls 9 and 11, and the partition walls between the pockets, but they must be discharged so the contents by the relative rotation are rubbed over all their sloping surfaces (note the direction of rotation in Fig. 100 9) from one pocket to another both in the circular series A—A², etc., and in the radial series A—E.

A feature of particular importance in this movement of the liquor is the rubbing (not 105 cutting) action over the very large area of all the gradually sloping surfaces of the hundreds of pockets in the disks. This extremely large area of such surfaces for the rubbing action desired is obtained by a relatively simple arrangement of the pockets which is the important and broad feature of my invention. Notice that if the direction of rotation in Fig. 9 were reversed, cutting action rather than rubbing action would 110 result to the great detriment of the operation of refining the cocoa, chocolate, or the like. Furthermore, in the reverse direction of rotation, consider the great area of the gradually sloping surfaces of the pockets 115 which would not effectively act on the liquor to either rub or cut it, the latter being undesirable in the use aimed at. It will be plain then by the comparison that the great area of effective rubbing surface (utilized 120 by proper direction of rotation) with the simple arrangement of pockets in association with the effective arrangement of the feeding grooves attain new and useful results for the purpose of volume production. 125 130

The described angular arrangement of the pockets and the radial and circular series arrangement of the sets of pockets is another feature of particular importance. Such arrangement causes the movement of the liquor by the relative rotation of the disks along a decidedly scroll-like path of many convolutions to the periphery. During this movement, the liquor is squeezed and rubbed over an extremely large area of the effective reducing surfaces of the disks. In other words, the liquor has a practically continuous movement in the scroll-like path and is throughout such path effectively beaten over the large reducing surfaces of the disks. The orderly and logical arrangement of the pockets not only results in effective and improved refining of the liquor but in a better predetermined control of the volume production. The feeding pressure for liquor may be increased and speed of rotation of the disks increased with good results in my present invention to an extent not possible so far as I am aware in the use of prior disks for the same purpose.

I am aware of the two patents to Kihlgren No. 1,098,325, and No. 1,098,324, both granted May 26, 1914, on structure for reducing cocoa, chocolate, and the like, and I do not wish to be understood as claiming anything shown in either of said patents as my invention.

I have now disclosed in detail the preferred form of my invention, but many other forms of arrangements will readily suggest themselves to those skilled in the art having for their object the use of the invention in a specific form differing from the precise one shown. For example, the specific form of the sets of pockets, the radial series of sets, the circular series of sets, may be varied in numberless ways and still embody the invention. I, therefore, desire to have the scope of the invention determined by the following claims interpreted in the spirit of the disclosure of one exact form rather than in the letter of the exact form shown.

What I claim is—

1. A reducing disk for cocoa, chocolate, and the like having on its reducing face a plurality of specially formed pockets arranged in substantially concentric series, the pockets of each series being generally separated from the pockets of adjacent series by dividing walls, the tops of which are in the same plane as the outer face of the disk, each of the pockets being much longer than it is wide and having one substantially normal longitudinal face and a second longitudinal face gradually sloping from the bottom of the pocket to the outer face of the disk, and a series of spaced feeding grooves extending outwardly from the feed opening at the center of the disk toward the periphery of the latter and sloping gradually toward and

terminating in the plane of the top of the dividing walls, the longitudinal axis of each pocket arranged at a small angle to said feeding grooves.

2. A reducing disk for cocoa, chocolate, and the like having on its reducing face a plurality of specially formed pockets arranged in substantially concentric series, the pockets of each series being generally separated from the pockets of adjacent series by dividing walls, the tops of which are in the same plane as the outer face of the disk, each of the pockets being much longer than it is wide and having one substantially normal longitudinal face and a second longitudinal face gradually sloping from the bottom of the pocket to the outer face of the disk, and a series of spaced feeding grooves formed generally like the pockets but deeper than the latter, with their inner ends open to the central feed opening of the disk and with their perpendicular faces arranged at a small angle to the longitudinal axis of each of an adjacent group of pockets, whereby the inner ends of many of the pockets will open into the feeding grooves.

3. A reducing disk for cocoa, chocolate, and the like having on its reducing face a plurality of specially formed pockets arranged in substantially concentric series, the pockets of each series being generally separated from the pockets of adjacent series by dividing walls, the tops of which are in the same plane as the outer face of the disk, each of the pockets being much longer than it is wide and having one substantially normal longitudinal face and a second longitudinal face gradually sloping from the bottom of the pocket to the outer face of the disk, and a series of spaced feeding grooves extending outwardly from the feed opening at the center of the disk to a point near the periphery of the latter where they slope gradually to the top of the dividing walls, the longitudinal axis of each pocket arranged at a small angle to said feeding grooves, the dividing walls between the ends of adjacent pockets in different series being arranged at an acute angle with respect to the feed grooves, whereby the ends of successive pockets in each series are located a slight distance nearer the periphery of the disk than the ends of succeeding pockets considered with respect to the direction of the disks' rotation past a fixed point.

4. A reducing disk for cocoa, chocolate, and the like having on its reducing face a plurality of specially formed pockets arranged in substantially concentric series, the pockets of each series being generally separated from the pockets of adjacent series by dividing walls, the tops of which are in the same plane as the outer face of the disk, each of the pockets being much longer than it is wide and having one substantially nor-

mal longitudinal face and a second longitudinal face gradually sloping from the bottom of the pocket to the outer face of the disk, and a series of spaced feeding grooves extending outwardly from the feed opening at the center of the disk toward the periphery of the latter and sloping gradually toward and terminating in the plane of the top of the dividing walls, the longitudinal axis of each pocket arranged at a small angle to said feeding grooves, certain pockets adjacent the feeding grooves opening only at their inner ends into the feed grooves and pockets adjacent the periphery opening at their outer ends to discharge their contents at the periphery.

5. A reducing disk for cocoa, chocolate, and the like, consisting in a disk face divided into segments by feed grooves extending from the feed opening at the center of the disk toward its periphery, the segments substantially covered by elongated pockets slanted backwardly and outwardly with respect to the feed groove for a given segment and the direction of planned rotation, such pockets having interior faces arranged to rise gradually from the bottom thereof to the outer face of the disk in a direction generally opposite to the described direction.

6. A reducing disk for cocoa, chocolate and the like, consisting in a disk face divided into segments by feed grooves extending from the feed opening at the center of the disk toward its periphery, each designed to feed a particular segment, each of such segments substantially covered by elongated pockets slanted backwardly and outwardly with respect to the feed groove for a given segment and the direction of planned rotation, dividing walls to mark off such pockets into radial series of sets, such dividing walls arranged in separate series, each successive one of which is arranged nearer the periphery of the disk and the

walls of each series arranged at an acute 45 angle with respect to the feeding groove of its segment.

7. Apparatus for reducing cocoa, chocolate, and the like, consisting in two opposed reducing disks, one rotatable with respect 50 to the other, each of which comprises a reducing face substantially covered with elongated pockets having reducing surfaces gradually slanting from the bottoms of the pockets to the outer surface of the disk face 55 in a general direction opposite to the direction of relative movement between the opposed disks, and feed grooves extending from the center of the disk toward its periphery and dividing the disk face into 60 generally radial series of pockets, the latter for each series being slanted backwardly and outwardly with respect to its feed groove so that each successive pocket in a 65 series is arranged nearer the periphery of the disk.

8. Apparatus for reducing cocoa, chocolate, and the like, consisting of two concentric spaced disks, a relatively rotatable plate having on opposite faces thereof two disk 70 faces arranged respectively in opposed relation to the spaced disk faces, all of such disk faces being substantially covered with elongated pockets having reducing surfaces gradually slanting from the bottoms of the 75 pockets to the outer surface of their disk face in a general direction opposite to the direction of relative movement between opposed disk faces, and feed grooves extending from the center of the disk toward its 80 periphery and dividing the disk face into generally radial series of pockets, the latter for each series being slanted backwardly and outwardly with respect to its feed groove so that each successive pocket in a 85 series is arranged nearer the periphery of the disk.

ALONZO LINTON BAUSMAN.
